Primary Examiner — Darlington Ly(74) *Attorney, Agent, or Firm* — Dicke, Billig & Czaja, PLLC(57) **CLAIM**

The ornamental design for a motorcycle handlebar grip, as shown and described.

DESCRIPTION

FIG. 1 is a perspective view of a motorcycle handlebar grip embodying my new design;

FIG. 2 is a left side elevation view thereof;

FIG. 3 is a right side elevation view thereof;

FIG. 4 is a top plan view thereof;

FIG. 5 is a bottom plan view thereof;

FIG. 6 is a front elevation view thereof; and,

FIG. 7 is a rear elevation view thereof.

The broken lines in the drawings illustrate portions of the motorcycle handlebar grip that form no part of the claimed design.

1 Claim, 7 Drawing Sheets(56)
